(57) **CLAIM**

The ornamental design for a sandal, as shown and described.

DESCRIPTION

FIG. 1 is a front left-side perspective view of a first embodiment of a sandal showing our my new design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

FIGS. 1-7 depict a first embodiment of a design for a left sandal; a second embodiment is a right sandal, which is a mirror image of the preceding embodiment thereof, is also claimed but not shown.

The broken lines appearing in FIGS. 1-7 are to show the environment and form no part of the claimed design. The dashed seam edge lines shown on the straps of the sandal upper depict stitching, which does form a part of the claimed design. The broken lines showing the remainder of the sandal show portions that form no part of the claimed design.
